[57] **CLAIM**

The ornamental design for a combined bottle and cap, substantially as shown and described.

DESCRIPTION

FIG. 1 is a perspective view of a combined bottle and cap showing my new design;

FIG. 2 is a front elevation view thereof;

FIG. 3 is a top plan view thereof;

FIG. 4 is a side elevation view thereof; and

FIG. 5 is a bottom view thereof.

The sides not shown are plain and unornamented.
